UNITED STATES PATENT OFFICE.

FRED AGUSTUS LEWIS, OF MILLERTOWN, NEWFOUNDLAND.

BILLIARD-CUE CHALKER.

1,841,376.

Specification of Letters Patent. Patented May 25, 1920.

Application filed May 21, 1919. Serial No. 298,642.

To all whom it may concern:

Be it known that I, FRED A. LEWIS, a citizen of the Dominion of Newfoundland, residing at Millertown, in the Province of 5 Twillingate and Dominion of Newfoundland, have invented certain new and useful Improvements in Billiard-Cue Chalkers, of which the following is a specification.

This invention relates to games and more 10 especially to billiards, pool and similar games wherein a cue is used and which needs chalking.

The invention is a chalk holder, and its object is to provide a device to be suspended 15 from the ceiling or other overhead support within reach of the player, against which he can put the cue and chalk it very quickly.

The invention consists in details of construction to be more fully hereinafter described and claimed and shown in the drawings herewith and in which—

Figure 1 is a side elevation of the entire device.

Fig. 2 is an enlarged sectional detail.

A cord or other support 1 hangs from the ceiling and is connected with the upper end of a cylinder 2 whose lower end is reduced internally and provided with a female thread 30 as shown at 3. Engaging this thread is a male thread 4 on a rod 5 slidably mounted within the lower end of the cylinder 2, the rod by preference having a head 6 at its upper end, normally resting on the shoulder 35 7 within the tube to prevent the disconnection of parts.

A light expansive spiral spring 8 is coiled within the cylinder and rests upon the head as shown.

To the lower end of the rod is attached 40 the chalk holder. Herein it is shown as a box or clasp 10 having a knob 11 at its top as usual, the knob being connected with the rod in any suitable manner. The cue is 45 illustrated at 12, and its tip at 13.

In use, the player grasps the cylinder in one hand and holds the cue in the other.

Bearing its tip 13 against the chalk indicated at 14, he pushes the cue toward the cylinder. The result is that the chalk holder 50 and rod are driven upward and as they move the thread 4 on the rod travels in the female thread 3 within the cylinder and the rod and chalk holder are given a rotary motion as they progress. Progression is resisted by the weight of the parts and by the expansive force of the spring 8. Of course, as the cue cannot rotate and the chalk does, the chalk is spread upon the tip 13 in a manner which will be clear. Having 60 chalked the tip, the operator releases his hold on the cylinder and the parts return to the position shown in Fig. 1.

The foregoing description and the drawings have reference to what may be considered the preferred or approved form of my invention. It is to be understood that I may make such changes in construction and arrangement and combination of parts, materials, dimensions, et cetera, as may 70 prove expedient and fall within the scope of the appended claim.

Having thus fully described my invention, what I claim as new and desire to secure by Letters Patent is:—

A cue chalker comprising a cylinder internally reduced at its lower end, the reduced portion containing a female thread, a rod having a male thread operating in the female thread of the reduced portion, a head 80 formed on the upper end of the rod fitting the cylinder, a chalk holder secured to the lower end of the rod, a knob formed on the chalk holder, said knob being of greater diameter than the rod, and a coil spring 85 received in the cylinder and having one end engaging the head on the upper end of the rod.

In testimony whereof I affix my signature in presence of two witnesses.

FRED AGUSTUS LEWIS.
